UNITED STATES PATENT OFFICE.

HEINRICH NOWIGK, OF COLOGNE, GERMANY, ASSIGNOR TO RICHARD ZANDERS, OF BERGISCH-GLADBACH, IN PROVINCE OF RHINELAND, GERMANY.

CYCLE TREADLE-BEARING.

SPECIFICATION forming part of Letters Patent No. 689,984, dated December 31, 1901.

Application filed October 4, 1900. Serial No. 32,000. (No model)

To all whom it may concern:

Be it known that I, HEINRICH NOWIGK, cycle-manufacturer, a subject of the King of Prussia, German Empire, and a resident of 5 Cologne, in the Province of Rhineland and Kingdom of Prussia, Germany, have invented new and useful Improvements in Cycle Treadle-Bearings, of which the following is a specification.

10 The present invention relates to treadle-bearings for cycles. They are intended to make it possible to easily adjust or tighten the various parts of the bearings and to secure the treadle in a very simple and convenient 5 manner, and at the same time while greatly reducing the breadth of the wheel at the treadle-bearings to give to the latter a greater length, thus making them run better than is the case with the bearings hitherto in use.

20 The improvement is shown in the accompanying drawings.

Figure 1 shows a vertical section of the bearing. Fig. 2 gives a section on line A A.

The crank *a* on the right-hand side engages 25 by means of a short pin *a'*, ending in a kind of wedge *b*, the part between the ends *d* of the corresponding longer axle-pin *r*, split by a slit *c* in the left crank. According to the degree with which the one crank is tightened 30 against the other the wedge *b* enters more or less in the corresponding notch of the other pin between the ends *d*, and the intermediate spaces *e* are diminished in proportion. In order to form the bearing on the right side and 35 to cause the right crank to be tightened against the left, the following arrangement is made: For a certain length the pin *r* has an external thread *f*, into which fits the inner thread of a socket *u*, which at the outer end 40 opposite the plate in the center of the crank *a* is provided with a plate-like rim running all around. This rim is turned up or back at the edge. This causes a gutter-like space to be formed between *u* and *v* at the outer end 45 for the reception of the bearing-cone and the bearing-cup *i*, between which the balls *k* lie and run. The cone *g* is externally guided with its long arm on the socket *u* already mentioned above. The bearing-cup has on 50 its long arm *l* an inner thread by which it is

screwed into the so-called "box" *m*, while into this box there is likewise screwed from the other side the corresponding cup *i* of the left bearing. Into a hollow of the plate in the center of the crank *t*, at the left bearing, are 55 fitted the head of the cup *i* as well as the cone *g*, while the pin *r* has a thickening *t'* in the direction of the crank *t*, on which the long arm *h* of the cone *g* is guided. The already-mentioned plate on the crank *t* engages by 60 means of a rim *w* on its inside and passes over the outer top rim of the left bearing-cup *i* and over the end of the tube-piece *x* of the cycle-frame, which receives the bearing-box *m*, as well as the adjoining parts, 65 and from which branch off the diagonal tube or stay *z* and the lower runs or rear-fork stays *z'* of the frame. The rim *a'* of the plate at the right crank engages the socket *u* over the bent-back edge of the ring *v* and is provided 70 with an outside thread. The latter is engaged by the thread of the chain-wheel *y*, which on the opposite side has a rim *w'* corresponding to the plate-rim *w* of the left crank, the latter rim in its turn engaging the 75 rim or socket-piece *x* of the cycle-frame. At the point where the rim *w'* engages the wheel *y* in the direction of the axle the wheel is continued in a projecting ring *y'*, which when all parts are fitted lies against the front surface 80 of the bent-back rim of the plate-ring *v* of the socket *u*. When the parts are being fitted, *y* is screwed only a very little with its thread on the outer thread of the rim *a'*, and then the other parts are fitted together. During 85 this operation the socket *u* is constantly pressed away from the crank *t* and toward *a* by means of a spring *s*, wound around the pin *r* and resting with its outer end against the shoulder *t'* and with its inner end against the ring *p* at the inner end of the socket *u*. The said inner end of the spring *s* lies in a longitudinal groove *o*, formed in the threaded portion *f* of the pin *r* and in a corresponding groove on the inside of the ring *p*, whereby 90 said ring and socket are prevented from turning upon the threaded portion *f*, while the spring itself is held from turning on the pin *r*. The chain-wheel *y* is then screwed onto 95 the threaded portion *a'* to its full extent, so

as to draw *a* inward and bring the rim edge of the plate of *a* into contact with the ring *y'* and the rim *w'* over upon the outer surface of the adjacent end of the socket-piece *x*. The 5 part *v* will thus hold the chain-wheel *y* against outward movement, while the said wheel will secure the crank *a* in position. By the same operation the wedge *b* is pushed between the ends *d* of the pin *r*, and thus all parts are 10 finally tightly fitted against each other. The bearings are adjusted or screwed tighter by turning the cups *l* in the inner thread at the ends of the box *m* on the one hand and on the other hand by turning the ring *p* and the 15 socket *u* against the thread *f* after the spring *s* with its end that prevents the turning has been drawn out of the groove *o*. The spring *s* is not very strong, so that it can easily be 20 removed with the finger from *o*, and after *p* has been turned be made to slip back into its position. By means of the notches *q* *p* can be turned with a suitable key.

In order to prevent the crank *a* from becoming loose in the wheel *y* when the rider 25 is backing or suddenly stopping—many experiments have proved that this will rarely or never happen—an apparatus may be attached for safety which in this direction compels the wheel *y* to go with the crank *a* or to 30 remain in connection with it, so that the latter, with regard to *y*, can make no separate motion or only an exceedingly slight one. Such an apparatus can be attached on the disk of *y* or to the spokes thus formed in the 35 form of a simple carrier or striking-pin *g'*, placed in the backward direction of *a* opposite to *y*, as close as possible to *a*, so that the latter on the crank only moving back a little would strike against it, thus being held 40 fast or carrying *y* along with it. Thus, for instance, a number of holes 5 with thread could be uniformly distributed on the disk of *y* or the spokes into which a pin can be 45 screwed from the side pointing toward the crank *a*. After the bearing has been tightened as much as possible by turning *y* this pin is made fast in that hole which in the final position of *a* to *y* is the next behind *a*, (in the direction in which the cycle moves.) 50 What I claim as my invention, and desire to secure by Letters Patent, is—

1. The combination with an inclosing sleeve or socket, of a two-part crank-shaft, one part having a threaded portion and a tapered recess to receive the tapered end of the other

part, fixed bearing members at the ends of the inclosing socket, movable bearing members, bearing-balls between the fixed and movable bearing-sections, a socket about the shaft and coupling the sections, except as to 60 endwise movement, together and threaded to engage the said threaded portion of the shaft, said socket having a projecting portion bearing against one of the aforesaid movable bearing members, an adjusting-ring connected to the inner end of the said threaded socket, means for preventing independent rotation of the threaded member of the shaft and the said threaded socket, a sprocket-wheel confined in place by said projecting 70 portion of the socket and having a threaded hub, and cranks carried by the shaft-sections, one of said cranks having a threaded surface to engage the threaded hub of the sprocket-wheel to draw the shaft-sections together, 75 substantially as described.

2. The combination with an inclosing sleeve or socket, of a two-part crank-shaft, one part having a threaded portion and a tapered recess to receive the tapered end of the other 80 part, fixed bearing members at the ends of the inclosing socket, movable bearing members, bearing-balls between the fixed and movable bearing-sections, a socket about the shaft and coupling the sections, except as to 85 endwise movement, together and threaded to engage the said threaded portion of the shaft, said socket having a portion bearing against one of the aforesaid movable bearing members, an adjusting-ring connected to the inner end of the said threaded socket, a spiral 90 spring encircling the recessed part of the shaft and connected thereto and to the adjusting-ring to hold the same against independent rotation, a sprocket-wheel confined 95 in place by said projecting portion of the socket and having a threaded hub, and cranks carried by the shaft-sections, one of said cranks having a threaded surface to engage the threaded hub of the sprocket-wheel to 100 draw the shaft-sections together, substantially as described.

In testimony that I claim the foregoing as my invention I have signed my name in presence of two subscribing witnesses.

HEINRICH NOWIGK.
